UNITED STATES PATENT OFFICE.

ALFRED MOORHOUSE, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed July 1, 1922. Serial No. 572,189.

To all whom it may concern:

Be it known that I, ALFRED MOORHOUSE, a citizen of the United States, and resident of Detroit, Wayne County, State of Michigan, have invented certain new and useful Improvements in Internal-Combustion Engines, of which the following is a specification.

This invention relates to internal combustion engines and particularly to the water cooling system thereof.

One of the objects of the present invention is the elimination of outside piping as much as possible and the consequent simplification of the construction.

Another object of the invention is to provide a water pump for forcing cooling water through the engine jackets with a thermostat at the outlet of the jacket and a short inside by-pass from the thermostat to the intake side of the pump, so that the pump will be low enough to be primed at all times and yet close enough to the thermostat to permit a short pipe connection therefrom to the pump.

Another object is to provide a combination side cover and distributing conduit for the cylinder water jacket, thus simplifying and improving the construction.

Other objects of the invention will appear from the following description taken in connection with the drawings, which form a part of this specification, and in which:

Fig. 1 is a side elevation of an engine and radiator embodying the invention;

Fig. 2 is an enlarged section of one end of the cylinder block shown in Fig. 1;

Fig. 3 is a horizontal section substantially on the line 3—3 of Fig. 2, extending the full length of the block;

Fig. 4 is a fragmentary vertical section on the line 4—4 of Fig. 3; and

Fig. 5 is a transverse vertical section on the line 5—5 of Fig. 2.

Referring to the drawings 10 represents generally an internal combustion engine preferably of the motor vehicle type and 11 is a radiator shown as mounted at the front end of the engine. A fan 12 is mounted just back of the radiator for the purpose of increasing the circulation of air through the radiator.

In the form of engine shown there is a single cylinder block 13 comprising six cylinders 14, mounted on the crank case 15 of

the engine. The cylinder block is water jacketed around its sides and on top as shown particularly in the various detailed views. This cylinder water jacket is indicated generally by the numeral 16. It is open at one side as shown at 17 and a cover 18 is secured over the opening as by a series of screws 19. This cover will be hereinafter more particularly described.

The cylinder block is preferably divided horizontally along the line 20 shown in the various figures so that there is the cylinder block proper and a cylinder head. The cylinder head is hereinafter designated as 21 and the water jacket 16 extends into it as shown particularly in Fig. 2, the jacket of the cylinder block proper and the separable cylinder head being connected by various vertical openings such as 22 shown in Fig. 2. Thus the water that is fed to the lower part of the cylinder jacket will flow through the openings 22 into the jacket of the cylinder head. The detachable head is secured in place by a series of bolts 21'.

At one end of the cylinder block the casting is formed with a compartment 23 with a large opening 24 therein, see Figs. 2 and 3. A pump unit 25 is adapted to be inserted through the opening 24 and into the compartment 23, a ring 26 which is bolted to the cylinder block securing the pump unit in position. This pump comprises a casing 27 in which is rotatably mounted a pump impeller 28 on a shaft 29, the casing having openings 30 at its inner side so that the water may be drawn in by the impeller and forced radially outwardly into the compartment 23 above described. A bracket 31 extends from the pump casing outwardly to form a bearing 32 for the extended end of the shaft 29 and the fan 12 above described is mounted on the end of said shaft. A belt 33 may be connected to any suitable rotating part of the engine for driving the fan and pump.

There is a connection from the lower part of the radiator 11 to the intake side of the pump and this is shown as a pipe 34 which connects with a conduit or passage 35 leading to the openings 30 to the pump impeller. Thus the operation of the pump will draw the water from the lower part of the radiator and force it into the compartment or chamber 23 hereinabove described.

The compartment 23 has an opening or

port 36 leading outwardly at the side of the cylinder block at the front end thereof adjacent the side opening 17 and the cover 18 above referred to extends over this port as shown particularly in Fig. 3. In Fig. 2 the port 36 is shown in dotted lines. Thus the cover 18 serves to direct the water from the port 36 through the large opening 17 in the side of the cylinder block and into the water jacket of the cylinder block. In order, however, to prevent the flow of cooling water being directed wholly against the front cylinder the cover 18 is made in the form of a distributing conduit. It comprises an outside imperforate plate 37 and an inside plate 38 separated from it, thus forming an elongated conduit. The inner plate 38 is arranged to leave an opening 39 opposite the port 36 and it is provided with a series of ports or openings 40 along its lower part so that the water will be somewhat evenly distributed to the various parts of the cylinder jacket.

The jacketed part of the cylinder head 21 overhangs the front end of the cylinder block immediately above the pump compartment and a thermostat 41 is mounted in this overhanging part of the cylinder head jacket and is arranged to control a double valve 42—43. These valves control the outlet from the jacket. The valve 42 controls a port 44 and the valve 43 controls a port 45, both of which ports lead from the water jacket. A passage 46 from the port 44 leads to an inside pipe or conduit 47 which passes downwardly through the water jacket 16 to the intake side of the pump and from thence through the pump and the port 36 and cover conduit 18 to the lower part of the cylinder water jacket. The port 45 communicates with a pipe 48 which leads to the upper part of the radiator 11 as shown in Fig. 1.

The action of the thermostat is as follows: When the engine is cold the thermostat 41 is in its contracted state as shown in Fig. 2 and the port 44 is open and the port 45 is closed. The water is circulated through the pump and the water jacket and upwardly through the port 44; thence it will pass through the passage 46 and the by-pass 47 back to the intake side of the pump and through the compartment 23 and port 36 to the cylinder water jacket, where the circulation continues. As soon as the water heats up by the operation of the engine the thermostat expands and closes the port 44 and simultaneously opens the port 45. This closes the by-pass to the pump and the water passes upwardly through the passage 48 to the top of the radiator 11. It then passes downwardly through the radiator and is cooled and then is drawn up through the pipe 34 and the passage 35 to the pump which forces it into the compartment 23 through the port 36 and opening 39 into the

cover distributor conduit 18 and into the lower part of the cylinder water jackets through the openings 40. The water then rises through the openings 22 to the upper part of the cylinder water jacket, that is, the water jacket of the cylinder head, and then to the forward part of that jacket around the thermostat where the circulation continues as before described.

While I have herein described in some detail a specific embodiment of my invention, which I deem to be new and advantageous and may specifically claim, I do not desire it to be understood that my invention is limited to the exact details of the construction, as it will be apparent that changes may be made therein without departing from the spirit or scope of my invention.

Having thus described my invention, what I claim and desire to secure by Letters Patent is:

1. In an engine, the combination of a cylinder having a water jacket and an outlet therefor, a thermostat controlling said outlet, and a by-pass pipe from the thermostat back to the cylinder jacket extending inside the cylinder jacket.

2. In an engine, the combination of a cylinder having a water jacket and an outlet therefor, a thermostat controlling said outlet, a pump for circulating water through the cylinder jacket to the thermostat, a radiator connected to the outlet and pump respectively, and a by-pass inside said jacket from the thermostat to the pump.

3. In an engine, the combination of a cylinder, a separable head mounted thereon, a pump adapted to supply cooling water to the jackets of said cylinder and head, a thermostat mounted in the head for controlling the water outlet therefrom, and a by-pass from the thermostat through the head jacket to the pump.

4. In an engine, the combination of a cylinder, a separable head mounted thereon, a pump mounted on the cylinder for supplying cooling water to the cylinder and head jackets, a thermostat mounted in the head for controlling the passage of water from the head jacket, and a by-pass controlled by said thermostat and extending therefrom through the head jacket to the pump.

5. In an engine, the combination of a water jacketed cylinder, a pump mounted to supply cooling water to the cylinder jacket, a thermostat mounted in the cylinder jacket adjacent said pump, and a conduit leading from the thermostat through the jacket to the pump.

6. In an engine, the combination of a water jacketed cylinder, a pump mounted to supply cooling water to the cylinder jacket, a thermostat mounted in the cylinder jacket immediately above the pump, and a pipe

- leading from the thermostat through the jacket to the pump.
7. In an engine, the combination of a water jacketed cylinder block, a pump mounted on the end of said block, a portion of the jacket of said cylinder overhanging said pump, a thermostat positioned in the jacket over said pump, a pipe leading from the thermostat to the pump and a valve 10 on said thermostat controlling said pipe.
8. In an engine, the combination of a cylinder block having a side opening in its water jacket, and a cover for said opening forming a conduit with a series of openings 15 to the water jacket.
9. In an engine, the combination of a cylinder block having a side opening in its water jacket, and a cover for said opening formed of inner and outer separated plates 20 forming a conduit, the outer plate being imperforate and the inner plate having distributing openings to the outer jacket.
10. In an engine, the combination of a cylinder block having a side opening in its water jacket, and having a pump compartment at one end, and a cover for said opening forming a conduit from said compartment to the water jacket.
11. In an engine, the combination of a cylinder block having a side opening in its water jacket, and having a pump compartment at one end, and a cover for said opening forming a conduit for receiving water from said compartment and distributing it 30 to the jackets of the various cylinders.
12. In an internal combustion engine, the combination with a cylinder block with water jacket on side and top thereof, of a pump mounted at one end of the cylinder block, a distributing conduit along one side of the block adapted to receive cooling water from the pump, an outlet connection at the top of the water jacket above the pump, a radiator connected to said outlet and pump 40 respectively, and an inside by-pass through the water jacket from the outlet connection to the intake side of the pump.
13. In an internal combustion engine, the combination of a cylinder block having a water jacket, a compartment formed at one end of the block separately from the water jacket, a distributing conduit for the jacket removably secured to the block, and a pump 50 arranged in said compartment to deliver into said conduit.
14. In an internal combustion engine, the combination of a cylinder block having a water jacket formed with a side opening and having a pump compartment formed at the end of the block separately from the jacket, said compartment having a side outlet opening adjacent the side opening in the water jacket, a pump in said compartment and delivering to said outlet opening, and a detachable cover extending over said water 60 jacket opening and said side outlet opening and forming a distributing conduit to receive water from said outlet opening and distribute it to the water jacket of the cylinder block.
15. In an internal combustion engine, the combination of a cylinder block having a water jacket formed with a side opening and having a pump compartment formed at the end of the block separately from the jacket, 70 said compartment having a side outlet opening adjacent the side opening in the water jacket, a pump in said compartment delivering to said outlet opening, a detachable cover extending over both said openings, and a perforated plate within the cover extending over the water jacket opening, said cover and said plate forming a distributing conduit to receive water from said outlet opening and distribute it to the water jacket.
16. In an internal combustion engine, the combination of a cylinder block having a water jacket formed with a side opening and having a pump compartment formed separately from the jacket, said compartment having an outlet opening adjacent and substantially in the plane of the side opening in the water jacket, a pump in said compartment delivering to said outlet opening, and a distributing conduit to receive water from said outlet opening and distribute it to the water jacket, said conduit comprising a perforated inner plate over the side opening of the water jacket, and an imperforate cover plate detachably secured to the cylinder block and extending over the water jacket opening and the pump outlet opening.
17. In an internal combustion engine, the combination of a cylinder block having a water jacket formed with a side opening and having a pump compartment formed at the end of the block separately from the jacket, said compartment having a side outlet opening adjacent the side opening in the water jacket, a pump in said compartment delivering to said outlet opening, a cover detachably secured to the cylinder block extending over said outlet opening and said water jacket opening and forming a distributing conduit to receive water from said outlet opening and distribute it to the water jacket, said pump being removable without disturbing said distributing conduit.
18. In an engine, the combination of a cylinder block having a side opening in its water jacket, and having a pump compartment at one end, a removable cover for said opening forming a conduit for receiving water from said compartment and distributing it to the jackets of the various cylinders, and a pump mounted in said compartment and adapted to be removed without disturbing said cover.
- In testimony whereof I affix my signature.
ALFRED MOORHOUSE.
